UNITED STATES PATENT OFFICE.

JOHN J. GREFENSTETTE, OF TOLEDO, OHIO.

HOT-AIR FURNACE.

Application filed June 14, 1927. Serial No. 198,788.

The present invention is directed to improvements in hot air furnaces.

The primary object of the invention is to provide a furnace wherein a series of baffle plates are mounted in vertical spaced relation in the fire pot thereof in order that the heat from the burner will be directed against the inner surface of the fire pot wall to effectively heat the same, whereby the fresh air will be thoroughly heated.

Another object of the invention is to provide baffle plates so constructed that they can be conveniently placed in the fire pot of a furnace already installed as an attachment thereto.

In the accompanying drawings:

Figure 1 is a vertical, sectional view through a furnace, showing the baffle plates in the fire pot thereof.

Figure 2 is a sectional view on line 2—2 of Figure 1.

Figure 3 is a transverse sectional view through a fire pot, showing a modified form of support for the baffle plates.

Figure 4 is a sectional view on line 4—4 of Figure 3.

Referring to the drawings, 1 designates the outer casing and 2 an inner casing, which, in the type of furnace shown, provides a fresh air inlet space 3 which communicates with the space 4 defined by the wall of the fire pot 5 and the hood 6. It will be obvious that the fresh air passing through the space 4 will be subjected to heat radiating from the wall of the fire pot.

The fire pot is of a conventional type and into which is directed the heat generated by the gas burner 7.

In order that the flame and heat from the burner will be directed against the inner surface of the fire pot 5 to effectively heat the same a plurality of baffle plates 8 are provided, the peripheries of which are spaced from the fire pot wall to permit passage of the flame and heat.

The baffle plates are formed from a plurality of semi-circular sections 9 and 10, in order that they may be conveniently passed through the door opening, not shown,

of the furnace, in order that they may be installed in a furnace already in use. Each section is provided with a pair of openings 11 for reception of the tie rods 12, four of which are used. The lower ends of the tie rods engage upon the upper ends of the pedestals 13, the lower ends of said pedestals resting upon the foundation 14. Spacing sleeves 15 are engaged upon the rods between the baffle plates and serve to maintain the baffle plates in vertical spaced relation, the lowermost baffle plate being engaged upon the collars 16 of the pedestals. The sections 9 and 10 after being engaged upon the rods 12 have their straight sides disposed in overlapped relation and retained thus by clamping bolts 17. The uppermost baffle plate is connected with the adjacent baffle plate by relatively short tie rods 18, and is maintained spaced therefrom by sleeves 19.

In Figures 3 and 4, the fire pot is shown equipped with a pair of lugs 20 which support baffle plates 21 which are also formed from sections 22 and 23, the sections 23 being hingedly connected to the fire pot wall, as at 24. These sections are also connected in overlapped relation by clamping bolts 25 and are used in connection with fire boxes especially equipped for the installation of the baffle plates by the provision of the lugs 20.

Having thus described the invention, I claim:

The combination with the fire pot of a furnace, of a plurality of pedestals mounted therein and provided with collars, a plurality of vertically spaced impervious baffle plates located coaxially with the walls of the fire pot, each baffle plate consisting of a pair of sections having their inner edges overlapped, means for securing the overlapped edges, tie rods passing through the sections and having their lower ends resting upon the pedestals, and sleeves engaged upon the tie rods and disposed between the baffle plates, the lowermost baffle plate resting upon said collars as and for the purpose set forth.

In testimony whereof I affix my signature.
JOHN J. GREFENSTETTE. [L. s.]
